UNITED STATES PATENT OFFICE

WASHINGTON L. HALL, OF PHILADELPHIA, PENNSYLVANIA, ASSIGNOR TO JAMES H. BILLINGTON COMPANY, OF PHILADELPHIA, PENNSYLVANIA, A CORPORATION OF PENNSYLVANIA

SHUTTLE

Application filed September 6, 1930. Serial No. 480,120.

This invention in general relates to shuttles of the type employed in textile industries, having for its object the provision of certain desired improvements in a shuttle of the kind indicated, with a view to a more efficient shuttle while effecting a substantial economy in manufacturing and operating expenses connected therewith.

A more particular object is to provide in a shuttle, a shuttle threading block of comparatively simple and inexpensive construction especially adapted for preventing the slipping or backing out of the thread from the shuttle while in action.

Another object is to provide an "automatic" shuttle threading block which may be stamped or pressed out of sheet metal, and of a design and construction eliminating superfluous weight, while insuring against a weakening or cutting away of the shuttle body hitherto liable in conventional types of shuttles.

Additional objects and advantages of the design, construction, arrangement and adaptation of parts will appear more fully in the details hereinafter set forth when taken in connection with the accompanying drawing in which:—

Fig. 1 is a fragmentary top plan view of a bobbin-containing shuttle to which my invention has been operatively applied;

Fig. 2 is a transverse sectional view taken on line 2—2 of Fig. 1;

Fig. 3 is a side elevational view of the "automatic" shuttle threading block as it appears disengaged from the shuttle body;

Fig. 4 is a perspective view of the "automatic" shuttle threading block;

Fig. 5 is an end elevational view of the same, and

Fig. 6 is a fragmentary top plan view of the shuttle with my novel shuttle threading block removed.

For the purpose of illustrating my invention I have shown in the accompanying drawing one form thereof which is at present preferred by me, since the same has been found in practice to give satisfactory and reliable results, although it is to be understood that the various instrumentalities of which my

invention consists can be variously arranged and organized and that my invention is not limited to the precise arrangement and organization of the instrumentalities as herein shown and described.

In the drawing wherein similar characters of reference indicate corresponding parts in the preferred form of the invention, A designates a conventional type of shuttle having the usual longitudinal recess or opening 1, wherein a bobbin 2 is shown which may be secured by any of the attachments (not shown) forming a part of the present day shuttles.

In one end 3 of the body portion 4 of the shuttle A I have formed an irregular-shaped chamber or recess 5 in which my automatic shuttle threading block B is adapted to be detachably inserted, being fastened therein by a screw or bolt 6 as shown in Figs. 1 and 2.

The chamber or recess 5 comprises a main countersunk well or pocket 7 defined by a ledge 8 at one end, an end wall 49 having a sloping portion 50 at another end, and a pair of laterally opposed walls 9 and 10 respectively, the wall 9 having a shoulder 10' with two small hook-accommodating sockets or holes 11. The wall 10 also is formed with a shoulder 12 having a notch or hole 13 to receive an element described hereinafter. A channel 14 communicating with the chamber 1 is cut through the wall 10 and serves to guide the end of the bobbin thread into the thread-outlet hole 15 of the shuttle A.

An alcove or auxiliary pocket 16 communicates with the countersunk well 7 for the reception of certain portions of the shuttle threading block B now to be described and forming an important feature of the present invention.

My shuttle threading block is formed preferably of a stamping of sheet metal, although it may be cast, molded, machined, etc. and is formed of a body portion 17 bent and folded to provide a substantial flat base 18, and a pair of opposed walls 19—20.

The upper portion of the wall 19 as clearly shown in Figs. 2 and 4 is bent at right angles and then flexed downwardly into an arcuate portion 21 which is arranged adjacent the

upper portion of the opposed wall 20, as clearly shown in Fig. 2, for the purpose of providing a thread guiding channel or groove 22. The said upper portion of the wall 19 as viewed in Fig. 2, has a struck out prong 23, the hooked end 24 of which is seated in the notch 18 formed in the shoulder 12 of the body portion 4. The wall 20, as shown in Figs. 4 and 5 is provided with a bent over portion or flange 26, the latter being formed with a pair of hooks 27, 28 which are adapted to be received in the notches or sockets 11 in the wall 9 of the body portion 3 of the shuttle A.

As best shown in Figs. 3 and 4, the base 18 is provided with a cut-out portion or channel 29 merging with a hole 30 in the wall 20, the adjacent edge 31 of which latter being sloped from the upper part to the base 18 and terminating in a small arcuate guiding hook 32, juxtaposed the hole 30, the purpose of which will appear hereinafter.

A fastening hole 33 is formed in the wall 19, this hole registering with a hole 34 formed in the opposed wall 20. Through the holes 33 and 34 the screw or bolt 6 is passed, the end 35 of the screw being threadedly engaged in the body portion 3 of the shuttle A.

As best shown in Figs. 1 and 2, the end 36 of the bobbin thread 37 has been passed through the guiding channel 22, the hole 30 and thence through the outlet hole 15 of the body portion 3 of the shuttle A, it being observed that a pair of pins 38 are secured in the body portion 3 immediately adjacent the hole 15.

To place the present device in operation the bobbin thread 37 from the shuttle 2 is first carried to the channel 22 and thence thrust downwardly past the sloping projecting end 39 of the arcuate portion 21, which as shown in Figs. 1, 3 and 4 has been extended beyond the major part of the body portion 17 of my shuttle threading block B.

The bobbin thread 37 is next carried around the arcuate end 41 of the edge 31 and then drawn downwardly past the small arcuate hook 32 into the small channel 29 in the base 18 which is formed between the said arcuate hook 32 and the adjacent edge 40 of the said base 18. The thread is next drawn through the outlet hole 15 in the body portion 3 of the shuttle A.

The actual placing of the bobbin thread 37 in position for the operation of the shuttle in its usual functions can be done in a second but has here been described in detail with a view to explaining the actual method involved in putting my shuttle into operation.

The shuttle threading block B is further provided with a small slot 42 in which a portion of a small friction pad 44 which may be felt, fabricated material, etc. is secured for tensioning the thread passing therethrough. The shuttle may now be placed in

any of the conventional machines or looms now employed and upon the actuation of same, the usual processes will be involved.

Heretofore much time, labor and added expense was involved by reason of the weakening of the shuttle body through the cutting or wearing away of the wood adjacent and engaged by the shuttle threading block.

As immense numbers of shuttles are employed in the textile industry involving a considerable expense, it will be seen that any means effective in prolonging the life of shuttles in reducing the wear and tear on same will be an important factor in reducing expenses in those industries, wherein shuttles of the present type are employed.

The present shuttle threading block may be threaded more readily than the conventional shuttle threading block by reason of the accessibility of the thread guiding channel elements forming part of the threading block which are adapted to coact in leading or permitting the thread to fall, or to be guided into the thread outlet hole 15 of the body portion 3 of the shuttle A. The arcuate portion 21 is particularly adapted to prevent the backing out of the thread from the shuttle, or in other words the unthreading of the shuttle in operation.

My shuttle threading block is preferably made of metal, such as iron, brass, etc., although any material suitable for the purpose may be employed. It will also be understood that in practice the exact size and configuration of all the various details may be varied within reasonable limits, without reducing the efficiency of the device provided that the general proportions of the device are preserved. The present shuttle threading block may be conveniently struck out of a sheet of material, bent and folded along the lines indicated, and after completion is simply pressed into the recess 5 and thrust downwardly until the base 18 abuts the flare of the well, or pocket 7. In this position, the various parts of my shuttle threading block B including the prong 23 and the hooks 27-28 will be found to fall into the recesses provided in the body portion of the shuttle A for their reception.

I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

Having thus described my invention what I claim as new and desire to secure by Letters Patent, is:

1. A shuttle threading block of the kind described comprising a body portion bent and folded upon itself to provide a pair of

opposed walls, one of said walls having a folded over part carried to a point adjacent the other of said walls to form a thread guiding channel therebetween, said first mentioned wall having an integrally formed securing hook, the other of said walls having a flange provided with a pair of hooks, and an element on said first mentioned wall formed integrally therewith for preventing the thread from backing out of said shuttle in action, said element consisting of an arcuate hook disposed adjacent a channel formed in the bottom of said shuttle eye.

2. A device of the kind described, in combination with a shuttle, a shuttle threading block formed of a stamping, said stamping having a pair of opposed walls each having a hook for engaging and positioning said shuttle threading block in a recess formed in said shuttle one of said walls having a bent upper portion forming in conjunction with the other of said opposed walls, a thread guiding channel, said thread-guiding channel serving to guide said thread into a thread receiving and thread-tensioning means, and fastening means in said threading block for detachably securing the same to said shuttle.

3. A shuttle threading block formed of a sheet metal stamping and having a chamber containing a thread tensioning instrumentality, said threading block including a bottom having formed integrally therewith a pair of opposed walls, oppositely disposed hooks on said walls, said opposed walls being provided with a thread guiding channel therebetween, one of said walls having means for preventing the backing out of thread from the shuttle threading block while in operation, said means including a slot leading to a thread outlet.

4. A shuttle threading block bent and folded upon itself to provide a chamber, a thread tensioning instrumentality secured in a slot formed in the body portion of said shuttle threading block, said body portion having a pair of opposed walls, having bent portions provided with oppositely disposed hooks for securing the said shuttle threading block in operative position in a shuttle, and additional means formed in said body portion, and said opposed walls for guiding a thread and preventing the accidental drawing out of said thread from said shuttle threading block when in operation.

5. A bobbin-containing shuttle of the kind described, comprising in combination a shuttle having a body portion provided with an irregularly shaped recess for the removable reception of a shuttle threading block, said shuttle threading block having a chamber formed therein, a friction pad enclosed within said chamber, and oppositely disposed hooks integral with the opposite walls of said shuttle threading block for securing same to said shuttle.

6. A shuttle threading block of the kind described, comprising a sheet metal stamping bent and folded to provide a pair of opposite walls, one of said walls being projected at right angles to the main portion thereof and then bent downwardly to a position adjacent the other of said walls for the forming of a thread receiving channel therebetween, said shuttle threading block having a slot for receiving a friction pad therein, and oppositely disposed hooks extending from said opposite walls for securing said shuttle threading block in a shuttle.
